VACUUM CLEANER OR SIMILAR ARTICLE

William J. Cook and Walter E. Moore, Trumbull, Conn.,
assignors to General Electric Company, a corporation
of New York

Application December 5, 1957, Serial No. 48,781

Term of patent 14 years

(Cl. D9—2)

FIG. 1.

Des. 182,454

PAGE 2

Fig. 2.

Des. 182,454

PAGE 3

Fig. 3.

Fig. 4.

Fig. 5.

Fig. 1 is a perspective view showing the front, top and one side of a vacuum cleaner or similar article embodying the new design.

Fig. 2 is a side elevational view thereof.

Fig. 3 is a bottom plan view thereof.

Fig. 4 is a top plan view thereof.

Fig. 5 is a fragmentary front elevational view thereof.

The dominant features of the design reside in the portions shown in full lines.

We claim:

The ornamental design for a vacuum cleaner or similar article, substantially as shown and described.
